UNITED STATES PATENT OFFICE.

HENRY S. BALDWIN, OF MIDDLETOWN, CONNECTICUT.

BREECH-LOADING ORDNANCE.

SPECIFICATION forming part of Letters Patent No. 614,821, dated November 29, 1898.

Application filed August 14, 1897. Serial No. 648,255. (No model.)

To all whom it may concern:

Be it known that I, HENRY S. BALDWIN, a citizen of the United States of America, residing at Middletown, in the county of Middlesex and State of Connecticut, have invented a certain new and useful Improvement in Breech-Loading Ordnance, of which the following is a description, reference being had to the accompanying drawings, wherein—

10 Figure 1 is a top view of the rear portion of the barrel of the gun and of the breech. Fig. 2 is a view in central vertical lengthwise section on the plane denoted by the broken line xx of Fig. 1 of the entire breech-loading mechanism. Fig. 3 is a side elevation view of the rear part of the gun and breech, with a part of the breech represented as broken away, so as to show interior construction. Fig. 4 is a top view of the movable breech-block. Fig. 5 is a front view of the movable breech-block. Fig. 6 is a right side view of the movable breech-block. Fig. 7 is a view in vertical cross-section of the part shown in Fig. 1 on the plane denoted by the broken line yy . Fig. 8 is a top or plan view of the extractor. Fig. 9 is a side view of the extractor. Fig. 10 is a rear view of a portion of the main operating-lever, the breech-block lever, and the connection between the two. 25 Fig. 11 is a side view of the forked retainer for the breech-block arm hereinafter described.

The object of the improvement is to simplify, strengthen, and cheapen the construction of breech-loading ordnance and to make 30 the operation thereof more efficient and durable.

In the accompanying drawings the letter a denotes the barrel of the gun, and b the breech thereof in a general sense. b' denotes the cartridge-channel in the breech, a channel for facilitating the entry of the cartridge c into the bore of the barrel. The breech is mortised through from top to bottom, the trend 40 of the mortise being slightly inclined forwardly at the top to the bore of the barrel.

The letter d denotes the movable breech-block, which has an up-and-down motion in the mortise through the breech just referred to to effect the closing and opening of the breech, the setting the cartridge home to its seat in the bore of the barrel, and the with-

drawal or extraction of the cartridge-case at the proper time. This up-and-down movement of the breech-block is not exactly at right angles to the trend of the bore of the gun, but is slightly inclined thereto, such inclination of movement being effected by the inclination of the mortise through the breech already referred to.

It is a primary purpose in the construction 60 of this mechanism to make the walls of the mortise through the breech the guides for the up-and-down motion of the breech-block, dispensing with feathers and splines, and thus attaining strength and solidity of construction, simplicity of construction, cheapness of 65 construction, and, to an improved degree, excluding the entrance of dust, water, rust, and the like between and into the operating parts.

The letter e denotes what may be termed 70 the "front" ways for the breech-block and e' denotes what may be termed the "rear" ways therefor. Between the front ways e there is a surface e'' , which from top to bottom is at right angles to the bore of the gun. 75 The breech-block d carries on its top the cartridge-channel d' , which at the front is given a downwardly-dipping bevel for coöperation with the rear end of the cartridge in forcing that cartridge to its seat in the chamber of 80 the gun. The front of the breech-block carries the cam or wedge d'' , the surface of which is adapted to the surface e'' , and it serves to give the cartridge its final forcing home to its seat in the chamber of the gun.

The letter f denotes the firing-pin, whose 85 firing action is given by the spring g . This firing-pin and spring are borne in and carried by the firing-pin case h . On the exterior of this case there are two radial spurs h' , which 90 serve to lock the firing-pin case into its seat longitudinally, fitting meanwhile in an annular groove made in the wall of the socket which contains the firing-pin case, being readily admissible to that groove when the firing-pin case is in a certain position rotarily and being locked in the groove by the subsequent 95 partial rotation of the firing-pin case. The rotation of the firing-pin case from this adjustment and position just described is prevented by the inner cocking-lever k , which 100 plays back and forth in a longitudinal slot in

the firing-pin case, its end entering a suitable mortise or socket in the body of the firing-pin.

The inner cocking-lever k and the outer cocking-lever k' are both fast (rotarily) upon the same shaft k'' . The outer cocking-lever k' is actually fast on shaft k'' . The inner cocking-lever k is fast to sleeve k''' , which is squared interiorly and fits upon a correspondingly-squared part of shaft k'' . The sear l , actuated by the sear-spring l'' , holds the cocking-levers and the pin in the cocked position when they are moved thereto, and their release for giving the firing-pin its firing or striking action is effected by a pull upon the trigger m . The sear l carries a fin l' , which fits into an annular groove in the surface of shaft k'' and holds it in place longitudinally.

The letter n denotes the extractor, which can be freely inserted from the rear into the extractor-way n' when the breech-block is absent from the breech-block mortise in the breech. This extractor bears upon its side a stud n'' , entering and coöperating with the extractor-groove n''' in the left side of the breech-block, the shape of which is such that the forward and back motion of the extractor is given while the breech-block is making the lower part of its up-and-down motion.

The letter o denotes the main operating-lever. It moves about one hundred and eighty degrees, rotarily, to effect the opening and closing of the gun. It is made to be practically fast on the same shaft o' as the breech-block arm p , which is turned over into a short crank-pin p'' at the end entering the groove p' in the right side of the breech-block.

In Figs. 2 and 3 the breech-block and the other parts are shown in the "closed" position. When the main operating-lever o is rotated a half-turn rearwardly from its position, as shown in Fig. 3, the coöperation of the breech-block arm p and the groove p' causes the breech-block to move downward and open the gun. At the same time and in this motion the breech-block arm p comes in contact with and operates the outer cocking-lever k' , and with it the inner cocking-lever k , so that this downward motion of the breech-block—the opening of the gun—cocks the firing-pin.

In order to give the breech-block the solidity and completeness of bearing which it has, especially upon the front ways e , peculiar provision has to be made for assembling the parts. The movable breech-block being absent from the breech, the shaft o' is inserted into its bearing from the inner side, with the breech-block arm p hanging straight downward, the forked retainer r not being yet in place. This allows the arm p to occupy its place, so that the crank-pin p'' , on the end of the arm p , is the only thing standing in the path of the breech-block to prevent its insertion from below into the mortise made for it in the breech. In order to do away with what would otherwise be an obstruction to this movement,

there is made in the right side of the breech-block the groove r' , the presence of which permits the breech-block to be inserted to its place in the breech. That insertion being effected, the shaft o' and arm p are moved inwardly a little till the pin on the end of that arm enters the groove p' . Then the forked retainer r is pushed into its place from below, the forks thereof, by their elasticity, springing over the shaft o' and serving to retain all the parts just mentioned in their proper operative places, and at the same time the forked retainer renders this wall of the mortise in the breech-block practically flush and continuous.

I claim as my invention—

1. In breech-loading ordnance, a mortise in the breech slightly inclined from a position perpendicular to the bore of the gun, having at the front thereof inclined ways e , and between said ways a recess e'' having a plane surface at right angles to the bore of the gun, in combination with a breech-block adapted to move up and down in said mortise, and provided on its front face at the outer margin thereof with inclined faces taking bearing on said inclined ways e , said breech-block having also on its front face between said marginal faces a wedge-shaped projection d'' , faced at right angles to the bore of the gun, whereby it is adapted to approach and recede normally to and from said plane surface e'' as the breech-block is moved up and down, in combination with the main operating-lever and the forked retainer for securing said operating-lever in place substantially as specified.

2. In breech-loading ordnance, a mortise in the breech slightly inclined from a position perpendicular to the bore of the gun, a breech-block movable therein, having in its side the slots $r' p'$, substantially at right angles to each other, in combination with a breech-block lever o , shaft o' , forked retainer r , breech-block arm p , having lug p'' , said lug adapted to engage with and reciprocate in the slot p' , as the lever o is oscillated, whereby said breech-block is moved up and down, substantially as specified.

3. In breech-loading ordnance, a mortise in the breech, a breech-block movable up and down therein, having in its face slots r' and p' , breech-block lever o , shaft o' , forked retainer r , arm p , and lug p'' , said lug adapted to engage with said slot p' , whereby said breech-block is operated, in combination with outer cocking-lever k' , inner cocking-lever k , and firing-pin f , substantially as specified.

4. In breech-loading ordnance, the mortise in the breech, the breech-block movable up and down in said mortise, having slots $r' p'$, a firing-pin borne in said breech-block, a cocking-lever k mounted on shaft k'' and engaging with said firing-pin, and an outer cocking-lever k' also mounted on shaft k'' , in combination with breech-block lever o , shaft o' , forked retainer r arm p , and lug p'' , whereby

- the breech-block is operated and at the same time the firing-pin is operated through said cocking-levers k , k' , substantially as specified.
5. In breech-loading ordnance, a mortise in the breech, said mortise slightly inclined from a position perpendicular to the bore of the gun, inclined ways e at the front of said mortise, a recess e'' between said ways, having a 10 plane face perpendicular to the bore of the gun, a breech-block having inclined faces on its outer front margins adapted to move on said inclined ways e , a wedge-shaped projection d' on said breech-block between said inclined faces, having a plane face at right angles to the bore of the gun, slots r' p' in the breech-block on the side thereof, operating-lever o , shaft o' , and arm p , having lug p'' , 15 said lug engaging with slot p' to operate the breech-block, in combination with firing-pin f , inner cocking-lever k , outer cocking-lever k' , grooved shaft k'' , and sear l , having fin l' engaging said groove, substantially as specified.
- 20 6. In breech-loading ordnance, a mortise in the breech, said mortise slightly inclined from a position perpendicular to the bore of the gun, inclined ways e at the front of said mortise, a recess e'' between said ways having a 25 plane face perpendicular to the bore of the gun, a breech-block d having the cartridge-channel d' downwardly inclined at the front, said breech-block having inclined faces on its outer front margins adapted to move 30 on said inclined ways e , a wedge-shaped projection d'' on said breech-block between said

inclined faces having a plane face at right angles to the bore of the gun, slots r' p' in the breech-block on the side thereof, operating-lever o , shaft o' , and arm p having lug p'' , 40 said lug engaging with slot p' to operate the breech-block, in combination with firing-pin f , firing-pin case h , having radial locking-spurs h' , inner cocking-lever k , outer cocking-lever k' , grooved shaft k'' , and sear l , having fin l' engaging said groove, substantially as specified.

7. In breech-loading ordnance, the two cocking-levers rotarily fast upon the same shaft and a groove in the surface of said shaft, 50 in combination with the sear carrying a fin fitting into said groove in the surface of said shaft, all substantially as described and for the purposes set forth.

8. In breech-loading ordnance, the sliding 55 breech-block, having the transverse slot therein, the main operating-lever having a lug engaging with said slot, means whereby said lug can be longitudinally withdrawn to permit the entrance of said block into position, 60 and means for locking said lug into operative relation with said slot, substantially as specified.

9. In breech-loading ordnance, in combination, the sliding breech-block, having slots 65 r' , p' , operating-lever o , shaft o' , arm p and lug p'' , and forked retainer r , substantially as specified.
